UNITED STATES PATENT OFFICE.

PETER J. PAULY, OF ST. LOUIS, MISSOURI.

IMPROVEMENT IN BOLTS FOR DOORS OF JAIL-CELLS.

Specification forming part of Letters Patent No. **155,105**, dated September 15, 1874; application filed August 1, 1874.

To all whom it may concern:

Be it known that I, PETER J. PAULY, of St. Louis, St. Louis county, Missouri, have invented a certain Improvement in Locks for Doors of Jail-Cells, of which the following is a specification:

My invention consists in attaching the sliding bolts that lock the cell-door to a lever, by which said bolts are operated, and the levers of a number of doors in a row are connected to a single sliding bar operated by a lever outside the corridor and inclosed within a locked case, so that the lever can only be operated (to lock or unlock the cell-doors) when the case-door is open. The operating-lever, when the cell-doors are locked, engages over a staple to receive a padlock.

In the drawings, Figure 1 is a front view. Fig. 2 is a plan.

A is the corridor, inclosed by grating B upon the outer side, and the cell-wall C on the inner side. D are the cell-doors, hinged at E, and having a hasp-bar, F, by which each door can be secured singly. g g are bolts, sliding in cleats H, and connected to a vertical bar, G, having a link, g', pivoted to the lower end of a lever, I, which is fulcrumed at i to the wall of the cell, and whose upper end passes through a notch or slot in the horizontal sliding bar J. The bar J extends from end to end of the row of cells. The outer end j of this

bar extends outside the corridor into a locked case, K, and is connected to a lever, L, fulcrumed at l, and whose free end is slotted for the passage of a staple, and is secured by a lock, M. By this lever L the bar J, lever I, and bolts g are moved either to lock or unlock all the cells simultaneously. k is the door of the case K, said door being fitted with any desired kind of lock. The lever L or lock M cannot be tampered with as long as the door k remains closed. N is the door of the corridor, the bolt O of which is arranged to slide into the case K, where it is secured by a padlock, P, passing through an eye in the end of the bolt.

It may be arranged, if desired, for the closing of the door to lock the corridor-door, and to hold it locked until the case-door is again opened. The opening of the case-door in this case would not unlock the corridor-door, as this would be done by a separate action.

I claim as my invention—

The cell-door D, bolts G g, cleats H, link g', and lever I, in combination with sliding bar J, case K, lever L, and lock M, substantially as set forth.

PETER J. PAULY.
